UNITED STATES PATENT OFFICE.

MABEL DAVISON, OF NEW YORK, N. Y.

DESIGN FOR AN ARM-BAG FOR LADIES' KNITTING OR SEWING.

47,533.

Specification for Design.

Patented July 6, 1915.

Application filed November 24, 1914. Serial No. 873,835. Term of patent 3½ years.

To all whom it may concern:

Be it known that I, MABEL DAVISON, a citizen of the United States, residing at No. 159 East Eighty-second street, New York city, in the county of New York and State of New York, have invented a new, original, and ornamental Design for Arm-Bags for Ladies' Knitting or Sewing, of which the following is a specification, references being had to the accompanying drawing, forming part thereof.

The figure is a plan view of an ornamental design for an arm bag for ladies' knitting or sewing.

I claim:

The ornamental design for an arm bag for ladies' knitting or sewing as shown.

MABEL DAVISON.
